LOCKING DEVICE FOR THE SLIDING MEMBERS OF AN EXTENSIBLE FRAME

Daniel A. Eberhardt, St. Louis, Mo.

Application December 18, 1947, Serial No. 792,398

4 Claims. (Cl. 287—58)

1

This invention relates to an improved clamp or lock for securing the extendible members of an extensible frame, such as a trouser creaser, in selected position.

More specifically, the invention pertains to an improvement to the device disclosed in U. S. Patent No. 2,294,967 for Adjustable Rod Joint, issued September 8, 1942 to Daniel A. Eberhardt. The improvement resides, in part, in the provision of a clamp which while permitting the free movement of the members outwardly to an extended position, automatically operates to prevent their movement inwardly to a closed or contracted position. In the patented device the clamp or lock is operative, when in its clamping position, to secure the adjustable section of the frame against movement in both directions.

It is an object of the invention to provide a clamp or lock of the character described which is economical to manufacture, and which is efficient in service and lasting in wear.

Other objects and advantages will become apparent as the specification proceeds and a more comprehensive understanding of the invention will be afforded from the following detailed description when considered in conjunction with the accompanying drawing, in which

Fig. 1 is a plan view of a trouser creaser embodying the instant invention,

Fig. 2 is a perspective view of a clamp or locking device embodying the instant invention and showing the parts thereof,

Figs. 3 and 4 are plan views of the clamp shown in Fig. 2, showing, respectively, the relationship of the parts in clamping position and released position, and

Figs. 5 and 6 are plan views of the clamp shown in Fig. 2, illustrating the same in modified forms.

For the purpose of disclosing preferred embodiments of the invention, the same has been shown and now will be described in connection with its use as a part of a trouser creaser. With reference to Fig. 1, this device takes the form of an extensible frame, which is well known in the art. Here, two thin strips 11 and 12, of material such as steel, are formed, respectively, with top arms 13 and 14 and bottom arms 15 and 16. The arms of the creaser may be associated with each other in one of several ways, one of which will be described for the top arms of the device, only. As shown in Fig. 3, the arm 14 has fixed to its end a sleeve 17 in which the arm 13 is free to slide. Similarly, a sleeve 18 (Fig. 1) is attached to the end of the arm 13

2

in which sleeve the arm 14 is free to slide. With this arrangement of the parts, the arms are held together closely and are free to move relative to each other. A clamp or locking device 19 is positioned with respect to each of the arms 13 and 14 to hold them against relative movement in selected positions. In a similar manner, the bottom arms 15 and 16 are held together by two sleeves 21 and 22 and are provided with a clamp 10 or lock 23 which is identical with the clamp 19.

Thus, the trouser creaser is provided with top and bottom elements which are extendible to move the strips 11 and 12 in the leg of the trouser to stretch and crease the same. For this 15 particular type of extensible frame, it is not required that the arms of the device be locked against outward movement. On the contrary it is desirable that they be free to move to extend the frame and that they be locked against inward 20 or contracting movement, only, at any extended position, within the limit of their movement, to which they are urged. The clamps or locks 19 and 23 of the structure just described, which perform this required function and which form 25 the subject matter of the instant invention, are identical and only one will be described in its preferred and modified forms.

Referring to the clamp 19, as viewed in Fig. 2, the same comprises a key 24 in which a slot 30 25 is made to receive the arm 13. The slot 25 is slightly larger than the arm 13 and the key 24 is thus free to rock on the arm 13 as indicated by the arrows in Figs. 3 and 4. The arm 14 is made with a bowed section 26 which, together 35 with the arm 13, forms a frame for the clamp or lock, a leaf spring 27 and portion of the key 24 being positioned therein. A pin portion 28 (Fig. 3) of the key 24 is passed into a hole 29 in the spring 27 to loosely connect these elements so 40 that the key may be rocked about the arm 13 as aforesaid.

The spring 27 is mounted on the arm 14 as 45 illustrated and urges the key 24 into its normal position as shown in full lines in Fig. 3. In this position the arms 13 and 14 are free to move outwardly, but the walls of the slot 25, being at an angle with the faces of the arm 13, present sharp edges which engage the latter and prevent inward relative movement of the arms.

When the key 24 is moved to the position it 50 occupies in Fig. 4, the walls of the slot 25 are substantially parallel with the faces of the arm 13 and the latter is free to move in either direction in the key. To hold the key in its releasing 55 position requires the continuous application of

force. When this force is removed the spring 27 acts to bias the key to its locking position.

In one of its modifications, the locking device takes the form illustrated in Fig. 5. Here, the arms 13 and 14, the sleeve 17, and the key 24 are the same as for the previous embodiment. The arm 14, however, is formed with a bowed section 31 which is different from that (26) of the previous embodiment. Further, a hole 32 is made in the arm 14 itself to receive the pin portion 28 of the key 24. The operation of this particular form of the locking device is the same as that just described.

For the modification illustrated in Fig. 6, the distinguishing feature resides in a differently shaped key 33, the arms 13 and 14, the sleeve 17, the bowed section 26 and spring 27 being the same as shown in Figs. 2-4. In this case the key 33 is slotted at 25 to receive the arm 13 and has a pin portion 28 which passes into a hole 29 in the spring 27 just as previously described. However, the key, rather than being straight, is bent to form a thumb tab 34 which lies substantially parallel to the arm 13. Release of the clamp, its operations, etc., are all the same as for that of the modification illustrated in Figs. 2-4.

Various changes may be made in the details of construction, within the scope of the appended claims, without departing from the spirit of this invention. Parts of the invention may be used without the whole and improvements may be added while retaining some or all of the advantages of the invention.

What is claimed is:

1. In a clamp for locking two slidable arms comprising rods of substantially constant cross section which are held together in substantially parallel abutting relationship one with the other, a key having an opening therein through which a first of said arms is passed, said opening being dimensioned proportionately to the dimensions of said first arm but larger in area than the cross-sectional area of said first arm, a bowed section formed in the second of said arms, and means for pivotally supporting said key from said bowed section of said second arm, said means applying a force directly to said key to rock the same about said first arm into a normal locking position.

2. In a clamp for locking two slidable arms comprising rods of substantially constant cross section which are held together in substantially

parallel abutting relationship one with the other, a key having an opening therein through which a first of said arms is passed, said opening being dimensioned proportionately to the dimensions of said first arm but larger in area than the cross-sectional area of the first arm, a bowed section formed in the second of said arms, and means for pivotally connecting said key to said second arm at a point falling on said bowed section thereof, said means applying a force directly to said key to rock the same about said first arm into a normal locking position.

3. In an extensible frame having a pair of rods with means for holding the rods substantially contiguous to each other and slidable one with respect to the other, the improvement comprising clamping means including a bowed section in one of said rods providing a recess adjacent the near face of the other rod, a key having an orifice through which said other rod passes and an end portion having a pivot thereon extending into said recess, and a socket in the first mentioned rod for receiving said pivot whereby said clamping means exerts a force acting directly on said key.

4. In an extensible frame of the character described having relatively adjustable arms, means on each of said arms embracing the other whereby said arms are secured together in parallel relation but relatively slidable endwise, the portion of one of said arms between said securing means being bowed outward from the other and having means providing a pin socket, a key having an opening therein through which said other arm passes and a pin portion seated in said socket, and said bowed portion exerting a force directly on said key, whereby relative movement of said arms in one direction causes rocking of said key to clamp said other arm against further movement.

DANIEL A. EBERHARDT.
